INVENTOR

Edward G. Thomas

UNITED STATES PATENT OFFICE.

EDWARD G. THOMAS, OF BOSTON, MASSACHUSETTS.

DESIGN FOR A SECTION-LINER GAGE.

SPECIFICATION forming part of Design No. 31,837, dated November 14, 1899.

Application filed September 6, 1899. Serial No. 729,666. Term of patent 7 years.

To all whom it may concern:

Be it known that I, EDWARD G. THOMAS, a citizen of the United States, residing at Boston, in the county of Suffolk and State of Massachusetts, have invented and produced a new and original Design for Section-Liner Gages, of which the following is a specification, reference being had to the accompanying drawings, forming a part thereof.

Figure 1 is an end elevation, and Fig. 2 a plan showing my invention.

The leading or material feature of my design consists in the shape or configuration of the gaps or openings A in the edge of the flat

piece B, each gap or opening being inclosed by an end surface C and bottom surface D, substantially at right angles to end surface C, and the end surface E projecting inwardly toward the end surface C over the space F.

Having described my invention, what I claim as new, and desire to secure by Letters Patent of the United States, is—

The design for a section-liner gage, as herein shown and described.

EDWARD G. THOMAS.
